MACHINE FOR TWISTING STRIP STOCK

Richard F. Heinemann, Oakland, Calif.

Application December 17, 1942, Serial No. 469,380

11. Claims. (Cl. 153—78)

My invention relates to improvements in apparatus for shaping strip material into evenly spaced spiral form.

The invention is directed to solving the problem of uneven pitch usually imparted to a strip when it is twisted between two throats, which unevenness is due somewhat to the unavoidable inequality of strength throughout said strip, causing portions of it to twist into a closer spiral than other portions.

The broad object of my invention is to provide apparatus by which accurately spaced and accurately shaped convolutions of any desired pitch can be imparted to strip stock; and particularly where closely spaced convolutions are desired.

One object of my invention is to provide means to vary the pitch of the convolutions either by changing the relative position of the two throats about their common axis or by moving the throats toward or from each other along their common axis, or by both means.

Another object is to provide means for one throat which enables the throat members to be adjusted to conform to the desired pitch and at the same time enable said members to space and form the convolutions accurately so that when said strip emerges from said throat it is perfectly formed.

Other objects and advantages of my invention not here enumerated will become evident from the following description and from the drawings, in which:

Fig. 1 is a general plan view partly in section of one form of machine;

Fig. 2 is a vertical sectional view taken on the line II—II of Fig. 1 and Fig. 13;

Figs. 3, 4 and 5 are diagrammatic side elevational views of the shaping portion of the apparatus, each adjusted to impart a different pitch to the strip material;

Figs. 6, 7 and 8 are views in perspective conforming to Figs. 3, 4 and 5 respectively;

Fig. 9 is a view in vertical elevation looking in the direction of the arrows IX in Fig. 4;

Figs. 10 and 11 are diagrammatic views showing the throats shifted about their common axis;

Fig. 12 is an enlarged detail view of the mouth and throat 35; and

Fig. 13 is a vertical cross-sectional view taken looking in the direction of the arrows XIII—XIII of Fig. 2 showing the mounting of throat A.

While in the course of this description I shall refer to the apparatus illustrated, I want it understood that this is done in compliance with the

patent statutes and not with the intention of limiting the scope of my patent to the precise details illustrated except as this may be required by the appended claims.

5 Referring now to Fig. 1, I have shown the general assembly of one form of machine to carry out my method of imparting convolutions to strip stock. It comprises the throat unit, generally designated at A and the forming roll 10 throat unit B. The balance of the apparatus deals with the drive and adjustment of these units.

The strip stock 20 enters the feed drive housing 21 in unit A from a spool or other stock pile, and is engaged by feed wheels 22, suitably driven by motor 12 through telescoping universal drive shafts 23 and connecting mechanism comprising spur gear 24, 25, 26, 27. Shafts 23 always rotate in constant speed ratio with respect to 20 motor 12. The telescoping shafts 23 with toggle joints 28 allow housing 21 to be shifted in its arcuate base 29 to get various angular settings of throat unit outlet member 35 in relation to wheel throat B between forming rolls 40, 41. 25 Wheels 22 are preferably spring pressed, as by spring 31, to insure adequate frictional contact on strip stock 20.

Feed housing 21 has a throat outlet portion 35 and is mounted in the sub-frame 30, which in 30 turn is carried in an arcuate slotted base 29, having the center of the arc in alignment with the bore in housing 21. This adjustment, made by loosening bolts 37, permits the long dimensions of throat unit outlet member 35 to be turned or 35 tilted along its axis with relation to the throat between forming rolls 40 and 41. This is the angle measured at b in Figs. 10 and 11.

As a further adjustment of feed housing 21 and throat unit outlet member 35 in frame 30, I provide slot 33 in frame 30 with a cap screw 34 threaded into housing 21, so that housing 21 and its throat unit outlet member 35 may be moved toward or away from forming rolls 40 and 41. This adjustment changes the length of 45 dimensions a on Figs. 3, 4 and 5.

By means of both the above adjustments, employed singly or together, I can vary the pitch of the convolutions given the strip 20.

Forming roll throat unit B is composed of a 50 pair of duplicate feed rolls 40 and 41, and driving means mounted in machine base frame 32. In operative effect these feed rolls form a rolling throat and, among other things to be enumerated, cooperate with throat unit outlet member 35 to give the desired twist to stock 20. Another

function of rolls 40, 41 is to run in the convolutions and assure that they are evenly spaced and accurately formed. This means that for stock 20 of different width or pitch, the faces 40a and 41a of the rolls will be shaped to suit. This fit of roll 41 in convolutions 20a is shown in Fig. 9.

Figs. 3 to 8 and particularly Figs. 3 to 5 show the reason why it is necessary to have rolls 40, 41 adjustable to fit the particular pitch being given stock 20. In Figs. 3 and 6 the pitch is long so that rolls 40 and 41 are set in planes more nearly parallel than in Figs. 4 and 7 where the pitch is short and rolls 40 and 41 rotate in planes almost at right angles to each other.

The correct angular setting for rolls 40, 41 can be determined for each pitch (see dotted lines p-p in Figs. 3, 4 and 5). Also, the correct contour for faces 40a, 41a can be determined for each pitch and width of stock 20. This will mean that a plurality of sets of rolls 40, 41 will be needed for a machine that is to be operated on various widths of stock 20, or to give stock 20 convolutions of different pitch. (See Fig. 9.) For example, in Fig. 9, if the pitch were greater (more turns to the foot) the faces 40a and 41a would have to be narrower or more pointed.

As each forming roll 40, 41 is supported and driven by identical means, a description of the left-hand unit in Fig. 1 will be given. Here again, it is not my intention to limit my invention to precise details or to exclude equivalent mechanisms which will accomplish the purpose of the form described.

Feed roll 41 is keyed to shaft 43 journaled in yoke 44 with bevel gears 45, 46 secured on each end. Bevel gear 45 is keyed to shaft 43 while gear 46 runs free and is held on by collar 47. Yoke 44 is recessed at 48 to allow free movement to roll 40.

Yoke 44 also provides the support for part of the drive means, including the drive gear 50 in mesh with gears 45, 46; and spur gear 51 which is keyed to or integral with gear 50. The sleeve portion 52 of gear 50 extends along yoke 44 far enough to support spacer 53 and a part of thrust bearing 54. The left-hand half of thrust bearing 54 is secured in recess 55 on adjustable thrust sleeve 56.

Thrust sleeve 56 is threaded in a member rising from base frame 32, the purpose being to be able to adjust rolls 40, 41 toward or away from each other to suit the thickness of stock 20 being worked on. When once adjusted, thrust sleeve 56 is locked by means of collar 60 and nut 61.

Yoke 44 extends through collar 60 and beyond. It has thread 62 to receive nut 61 and key way 63 to receive lug 60a to lock collar 60 to it. The purpose of this particular locking is to permit use of collar 60 (with its indexing scale 64) to position shaft 43 and roll 41 at any predetermined angle for the pitch desired. (See Figs. 3 to 5.) This positioning of yoke 44 and roll 41 may be done by worm 65 and pinion 66, the latter being keyed to yoke 44. A hand wheel 67 aids in rotating worm 65.

When nut 61 is loosened, yoke 44 may be moved axially with relation to base frame 32 by rotating thrust sleeve 56 or it may be moved radially by rotating hand wheel 67.

Gears 51 are driven by pinions 70, 71 driven by motor 72 or other suitable source of power. The gear ratio between forming rolls 40, 41 and feed rolls 22 is preferably such that the peripheral speed of each corresponds with the speed of stock

20 in feed drive housing 21. Actually, this will call for a slightly slower peripheral speed for rolls 40, 41 than for rolls 22 because when twisted, stock 20 becomes shorter. The thing to be avoided is in having the relative speed such that rolls 22 will force the stock through throat unit outlet member 35 faster than rolls 40, 41 are forming it. This will cause a buckling and uneven pitch on stock 20. Practically, I have found the best way to be for rolls 40, 41 to be exerting a pull on stock 20, requiring it to slip slightly between rolls 40, 41 or rolls 22 or both—as this assures a taut strip of stock 20 between the sets of rolls 40, 41 and 22.

To obtain the drive I provide a variable speed device on the end of motor shaft 73, comprising a face plate 74. A second face plate 75 is mounted on end of shaft 76. Movement of plate 74 is transmitted to plate 75 through idler roll 77 mounted in supports rising from base frame 32 so that it can be shifted along shaft 78 by the usual yoke 79. A spring 80 keeps the plates 75, 74 and idler 77 in good driving contact.

In Fig. 12 is shown the preferred shape of throat unit outlet member 35 having the flared faces to minimize the friction and stress on strip 20 as it is shaped.

The operation of my device is as follows:

Assume it is desired to convert strip stock 20 into spiral stock. The first step is to feed stock 20 into feed housing 21. The latter will have been chosen with a throat unit outlet member 35 to fit the dimensions of stock 20.

Throat unit outlet member 35 is then adjusted toward or away from forming rolls 40, 41 to the position *a* previously calculated to give the desired pitch to stock 20 (see Figs. 3 to 5). If sufficient pitch cannot be obtained by this adjustment, throat unit outlet member 35 may be rotated on its axis by loosening cap screws 37 so as to change the angle *b* between the plane of throat unit outlet member 35 and the plane of wheel throat 40, 41. (See Figs. 10 and 11.) The pitch will be a factor of this angle *b* and the distance *a* between throat unit outlet member 35 and rolls 40, 41.

The next adjustment is to loosen lock nuts 61 and by rotating thrust sleeves 56 to set forming rolls 40, 41 with a clearance equal to the thickness of stock 20.

While nuts 61 are still loose, the next step is to turn handwheels 67 to bring forming wheels 40, 41 into the proper angular position (previously calculated to a scale to correspond with dials 64) to fit the contour that strip 20 should assume as it passes between rolls 40, 41 (see Figs. 3 to 5 and 9). When set, nuts 61 are tightened.

The next thing to set is the speed regulator idler 77 so wheels 22 turn with a peripheral speed calculated to feed strip 20 at exactly the speed it is being formed by rolls 40, 41, or at slightly less speed. Thus the strip between rolls 22 and rolls 40, 41 is under tension and not compression.

The machine is now ready to operate. Strip 20 should be inched through throat unit outlet member 35 and stopped short of rolls 40, 41 long enough for the operator to give the projecting end of strip 20 a twist which will facilitate its entry into the throat gap between rolls 40, 41. When the machine is restarted, strip 20 will feed in between rolls 40, 41 and the proper pitch will be imparted to strip 20. As it leaves rolls 40, 41 it is completely formed with accurate, evenly spaced convolutions 20a, and passes through bushing 80.

Another way of describing the means for adjusting the rolls 40 and 41 and their respective shafts for varying pitches, is to say that these rolls or shafts are moved about a line that includes a diameter of both rolls. This is clear from Figs. 3, 4, and 5, for it will be seen that a diameter on each roll is in substantial alignment.

What I claim is:

1. In a machine for making spiral strip stock, the combination of a frame, a pair of yokes journaled therein on a substantially common axis, means for securing said yokes against rotation in selected positions, a shaft rotatably journaled in each yoke at right angles to the above axis, a forming roll secured to each shaft, a bevel gear secured to each shaft, drive gears enmeshed therewith and rotating about each yoke axis, means for rotating said drive gears, a feed housing mounted in said frame, and having a throat unit outlet member substantially fitting said strip stock, means for moving said throat member toward or away from said forming rolls, means for rotating said throat member about its axis and securing it in selected positions, rotating feeding means in said feed housing, a variable drive connecting said rotating means with said forming rolls whereby their relative speeds may be changed to suit.

2. In a machine for making spiral strip stock, the combination of a frame, a pair of yokes journaled therein on a substantially common axis, means for securing said yokes against rotation in selected positions, a shaft rotatably journaled in each yoke at right angles to the above axis, a forming roll secured to each shaft, a bevel gear secured to each shaft, drive gears enmeshed therewith and rotating about each yoke axis, means for rotating said drive gears, a feed housing mounted in said frame, and having a throat unit outlet member substantially fitting said strip stock, means for moving said throat member toward or away from said forming rolls, rotating feeding means in said feed housing, a variable drive connecting said rotating means with said forming rolls whereby their relative speeds may be changed to suit.

3. In a machine for making spiral strip stock, the combination of a frame, a pair of forming rolls, a shaft supporting each roll and to which it is secured, oppositely set yokes in which said shafts are journaled, said yokes in turn being journaled in said frame, means for rotating and securing said yokes against rotation in selected positions to thereby change the angular relation between the planes of rotation of said forming rolls, drive means to rotate said roll supporting shafts, and a feed throat outlet member spaced away from said rolls and positioned to hold said strip stock in a twisted position in relation to its position while engaged by said rolls.

4. In a machine for making spiral strip stock, the combination of a frame, a pair of forming rolls, a shaft supporting each roll and to which it is secured, oppositely set yokes in which said shafts are journaled, said yokes in turn being journaled in said frame, means for rotating and securing said yokes against rotation in selected positions to thereby change the angular relation between the planes of rotation of said forming rolls, drive means to rotate said roll supporting shafts, a feed throat outlet member spaced away from said rolls and positioned to hold said strip stock in a twisted position in relation to its position while engaged by said rolls, and means for changing the position of said feed throat outlet member with respect to said forming rolls so as to vary the twist imparted to said stock.

5. In a machine for making spiral strip stock, the combination of a frame, a pair of forming rolls, a shaft supporting each roll and to which it is secured, oppositely set yokes in which said shafts are journaled, said yokes in turn being journaled in said frame, means for rotating and securing said yokes against rotation in selected positions to thereby change the angular relation between the planes of rotation of said forming rolls, drive means to rotate said roll supporting shafts, a feed throat outlet member spaced away from said rolls and positioned to hold said strip stock in a twisted position in relation to its position while engaged by said rolls, means for propelling said strip stock in said feed throat outlet member, and a variable drive means between said strip propeller and said feed rolls whereby the relative speed of each may be controlled.

6. In a machine for making spiral strip stock, the combination of a feed housing having at one end, a feed throat outlet member to fit said stock, means for propelling the stock in said housing, a pair of forming rolls arranged to contact opposite sides of said stock adjacent a line extending in axial alignment with the bore of said feed housing, a driven shaft supporting each roll, and means for driving said shafts, said driving means and said means for propelling the stock in the feed housing having a variable drive connection whereby the stock while moving between said rolls and said propelling means may be held under tension.

7. In a machine for making spiral strip stock, the combination of a feed housing having at one end, a feed throat outlet member to fit said stock, means for propelling the stock in said housing, a pair of forming rolls arranged to contact opposite sides of said stock adjacent a line extending in axial alignment with the bore of said feed housing, a driven shaft supporting each roll, means for mounting said shafts so they may be shifted and thereby change the angle between the planes of rotation of said rolls, means for securing said mounting means in any predetermined position, and means for driving said shafts, said driving means and said means for propelling the stock in the feed housing having a variable drive connection whereby the stock while moving between said rolls and said propelling means may be held under tension.

8. In a machine for making spiral strip stock, the combination of a feed housing having at one end a feed throat outlet member with surfaces to fit against opposite sides of said stock and hold it against rotation, a pair of forming rolls spaced adjacent a line extending in axial alignment with the axis of said feed housing, a driven shaft supporting each roll, means for adjusting said rolls about a line that includes a diameter of both rolls, means for securing said shafts and rolls in any such predetermined position, and means for driving said shafts regardless of the positions into which they may be moved.

9. In a machine for making spiral strip stock, the combination of a feed housing having at one end a feed throat outlet member with surfaces to fit against opposite sides of said stock and hold it against rotation, means for feeding strip stock therethrough, driving means for said feed means, a pair of forming rolls spaced adjacent a line extending in axial alignment with the axis of said feed housing, a driven shaft supporting each roll, means for adjusting said rolls about

a line that includes a diameter of both rolls, means for securing said shafts and rolls in any predetermined position, and means for driving said shafts regardless of the positions into which they may be moved.

10. In a machine for making spiral strip stock of varying pitch, the combination of a feed throat outlet member with surfaces for holding said stock against rotation therein, a pair of forming rolls mounted to rotate in planes which intersect, means for driving said rolls, and means for adjusting said rolls about a line that includes a diameter of both rolls to vary the pitch imparted to the strip stock.

11. In a machine for bending spiral strip stock of varying pitch, the combination of a feed throat outlet member with surfaces for holding said stock against rotation therein, a pair of forming rolls mounted substantially in alignment with said throat to rotate in planes which intersect, means for driving said rolls, and means for changing the distance between said throat and said forming rolls, whereby the pitch in the strip stock may be varied.

10

RICHARD F. HEINEMANN.
